UNITED STATES PATENT OFFICE.

PAUL BLOT, OF PARIS, FRANCE, ASSIGNOR TO SOCIETE BLOT-GARNIER & CHEVALIER, OF PARIS, FRANCE.

ELECTROMECHANICAL LAMP.

Application filed March 14, 1922. Serial No. 543,759.

To all whom it may concern:

Be it known that I, PAUL BLOT, a citizen of the French Republic, and a resident of the city of Paris, France, have invented Improvements in Electromechanical Lamps, of which the following is a full, clear, and exact description.

In known electro-mechanical pocket lamps, the contact device of the bulb and the connecting device between the armature and the bulb are made in a manner which is too precarious for the work of such an apparatus, which is liable, in the ordinary course of use, to violent jars and shocks.

13 In fact, it frequently happens that, with the known contact devices, a fairly heavy jar will displace the contact and put out the light. A shock of this kind also frequently breaks the wire connecting the armature 20 with the bulb contact, a circumstance which necessitates the lamp being taken apart completely in order to remake the connection.

Finally, the bulb contact devices can only be applied to lamps with a metal casing, 25 since it is only by means of the latter that the circuit can be completed.

In some of these lamps the hub of the magnet comprises a ratchet device with loose rollers, the cover of which device is carried 30 by the ratchet and leaves an appreciable space between its outer edge and the interior housing of the barrel. This arrangement presents the following serious inconvenience:

35 Under the action of a somewhat violent shock, the rollers shift round into a position at right angles to the normal, owing to the space aforesaid, and escape from the barrel, so that the wheel gear is no longer actuated 40 by the operating handle.

The object of the present invention is to remedy the various inconveniences mentioned, and relates to an improved electro-mechanical lamp having the following essential features:

45 The bulb contact is composed of a flexible metallic strip mounted on the metallic cage supporting the electric generator and its driving gears and is in contact with the male member of the head carrying the bulb, the said strip carrying an insulated contact-piece to which is attached the conductor from the armature and which contacts with the insulated contact-piece on the bulb.

50 According to one embodiment, this con-

tact is formed by a very flexible strip of steel bent round at right angles and secured, by its horizontal branch on the cage housing the gears, said branch carrying the insulated contact-piece whilst the vertical branch is in contact with the male member of the head of the bulb in order to make the necessary contact.

In another embodiment, the metallic strip is mounted on one of the spindles of the gears and is connected, by means of the insulated contact-piece, with a metal cap in which the bulb is screwed.

The invention also has for its object a device for conveying current to the bulb, 70 wherein the conductor conveying the current to the insulated contact-piece, is flexible and terminated in the female member of a push button adapted to fit on the male member to which the armature conductor is connected and which is secured on an insulated plate mounted, either on the cage carrying the electric generator and its driving members, or on the hub of the armature.

Finally, the invention also relates to a ratchet device with loose rollers, arranged in such a manner as to keep the rollers in their proper position and to prevent them from escaping out of the barrel.

In order that the invention may be clearly understood, a form of construction of the improved electro-mechanical lamp will be described hereafter with reference to the accompanying drawing and by way of example only.

Fig. 1 is an inner front elevation of the whole of the lamp, the casing being shown in vertical section and the bulb taken out of its housing.

Fig. 2 is a partial section made according to line 2-2 of Fig. 1, showing the first form of construction of the contact of the bulb.

Fig. 3 is a vertical section of a modification.

Fig. 4 is a partial cross vertical section made according to line 4-4 of Fig. 1.

Fig. 5 is a vertical section of the ratchet and movable roller device made according to line 5-5 of Fig. 4.

The electro-mechanical lamp illustrated in Fig. 1, comprises an electric generator of the magneto type, housed in a metal cage formed by two plates 2 held at a suitable distance apart by three tubular stays, and

secured within the casing 3 by three bolts 2^a fitted in the walls of the said casing and in the stays connecting the plates 2. These plates 2 are cut out as shown in the drawing, so as to form the supports necessary for mounting the operating lever as well as the gears for imparting a very rapid rotary movement to the multipolar magnet 5 of the electric generator about the shaft 6 on which is rigidly mounted the armature 7 of said generator.

The casing 3, which is constituted by two similar shells engaged with each other and made of metal or other stamped or moulded material, is provided at its upper part with an inclined wall in which is mounted a socket 3^a adapted to receive the male member 13 of the electric bulb and to present the latter in a position inclined on the axis of the apparatus so as to light the space in front of the user, the hand remaining in its natural position.

According to the invention, the current from the armature 7 is conveyed, in the form of construction shown in Figs. 1 and 2, to the contact of the bulb 8 by means of a very flexible strip of steel 9, bent round at right angles and secured, at one end, on the cage 2 containing the gears, by means of a screw or rivet 10.

The horizontal branch of this strip 9 carries at its centre an insulated contact piece 11, to which is riveted or soldered one end of a flexible wire 12, the other end being connected to the armature, as will be explained later, by a movable connecting device.

The vertical branch of the said metal strip 9 is directed so as to rub against the male metal member 13 of the head of the bulb and to thus ensure the necessary contact and complete the circuit of the said bulb.

The horizontal branch is disposed in such a way that, whatever the differences in the length of the bulb caps, contact is always ensured by the powerful pressure due to the resiliency of said branch, the bulb screwed home forming, with the flexible blade an invariable aggregation which cannot be disturbed by any jar or shock. Moreover, the arrangement of the vertical branch and its permanent contact with the metal cap of the bulb ensure the body contact and enable the circuit of the said bulb to be completed even with a casing of insulating material.

Finally, the immovable position of the aforesaid contact in relation to the cage 2, together with the pressure which it exerts on the centre of the bulb cap, prevent the lamp from being extinguished through imperfect or bad contact.

In the form of construction illustrated in Fig. 3, the metal strip 9, provided with

the insulated contact piece 11, is mounted on the axis of oscillation 14 of the operating lever 4, and carries a metal cap 15 riveted on the said strip by the insulated contact-piece 11 which, as already mentioned, is connected to the armature conductor by a flexible wire 12.

This arrangement, like the foregoing gives the same solidity and ensures the same reliability of action whatever the shocks or jars to which the lamp may be exposed, this latter receiving the current from the armature when the said lamp is screwed home in the cap 15 which, as in the preceding case, ensures body contact whether the casing be of conducting or insulating material.

The conveyance of the current to the insulated contact 11 of both the systems of contacts described above is effected in the following manner:

The armature conductor is riveted or soldered on to the male member 16 of a push button secured on a plate 17 of insulating material mounted friction tight on the hub 18 of the armature and is pressed firmly against the plate 2 of the cage when the armature is mounted in said cage, so as to prevent any angular displacement of said plate 17 and of the push-button member 16 which it carries.

The flexible wire 12 adapted to connect the armature with the insulated contact piece 11 is secured to the latter as already described, and is of sufficient thickness to prevent fracture through mechanical stress at any time.

Its free end is riveted or soldered to the female member 16^a of the push button, so that the connection is thus divided in two parts which can be easily and quickly disconnected and enable the whole to be easily taken to pieces and fitted up again very easily in case of repair to the lamp or changing the armature.

Moreover, the very small length to which is reduced the issue of the armature conductor and the application of the latter against the insulating plate 17 protects this conductor from any rupture, under the action of repeated and even very violent shocks.

The hub 19 of the magnet of the improved electro-mechanical lamp above described may conveniently comprise a ratchet and movable roller device in which the said rollers 20 and the ratchet 21 integral with the driving pinion 22 are arranged within a chamber 23 formed in the magnet hub and closed by a cover 24 directly beaded on the said hub, this cover being perforated with a central opening through which is engaged the pinion 22.

The arrangement of this cover, which does away with any free space between its

outer edge and that of the chamber 23, allows to exactly hold in place the rollers 20 within the chamber, so that these rollers cannot take a wrong position and that the 5 ratchet device, which resists to the most violent and abnormal shocks, will never brake the gears, will not wedge and will always act what ever may be the speed imparted to the magnet.

10 It results therefrom that with a smaller muscular effort on the operating lever, a longer duration of light is obtained.

15 The above constructional arrangements are of course given by way of example only, and the forms, materials and dimensions of the various constituent parts may be varied without departing thereby from the principle of the invention.

Claims.

20 1. An electro-mechanical pocket lamp comprising a casing,—a cage secured in the said casing,—an electric generator of the magneto type and its driving members carried by the said cage,—a metal socket on an 25 inclined face of the casing,—an electric bulb secured on the said socket,—a resilient metal strip secured on the cage and in contact with the metal cap of the electric bulb,—an insulated contact-piece on the said strip and 30 in contact with the insulated contact-piece of the said bulb,—means for conveying the current from the electric generator to the insulated contact piece of the resilient metal strip,—means for ensuring the actuation of 35 the rotary magnet.

2. An electro-mechanical pocket lamp comprising a casing,—a cage secured in the said casing,—an electric generator of the magneto type and its driving members carried 40 by the said cage,—a metal socket on an inclined face of the casing,—an electric bulb secured on the said socket,—a resilient metal strip bent at right angles and one of the branches of which is secured on the cage, 45 an insulated contact piece on the said branch and in contact with the insulated contact-piece of the electric bulb, the other branch of the metal strip being in contact with the metal cap of the head of the said bulb,—a flexible 50 wire connected at one of its ends to the insulated contact-piece of the metal strip, the female part of a push button being secured

to the other end of the flexible wire and adapted to fit on the male member connected to the armature conductor and secured on an 55 insulating plate mounted on the armature.

3. An electro-mechanical pocket lamp comprising a casing,—a cage secured in the said casing,—an electric generator of the magneto type and its driving members carried by the said cage,—a metal socket on an inclined face of the casing,—an electric bulb secured on the said socket,—a resilient metal strip mounted on the axis of the operating lever,—an insulated contact-piece on the 60 said strip,—a metal cap connected to the said strip by the insulated contact-piece,—an electric bulb screwed in the said cap, the insulated contact-piece of the said bulb being in contact with the insulated contact- 65 piece of the resilient metal strip,—a flexible wire connected at one of its ends to the insulated contact-piece of the metal strip, the female part of a push button being secured to the other end of the flexible wire and 70 adapted to fit on the male member connected to the armature conductor and secured on an insulating plate mounted on the armature.

4. In an electro-mechanical pocket lamp, a rigid hub, an armature mounted on said 80 hub, an insulating plate rigid upon the hub, a bulb socket, and means providing part of the current connection between the armature and bulb socket comprising a flexible 85 wire leading from the socket, and a snap fastener having one member at the end of said wire and another member mounted on said plate, said member receiving one of the armature conductors.

5. In a device of the character described 90 a fixed shaft, a multipolar magnet, a hub journalled on the shaft carrying the magnet and having a chamber, a driving pinion loose on the shaft and having an end extending into the chamber, a ratchet carried 95 by said end, rollers disposed between the ratchet and chamber wall to grip said wall upon rotation of the ratchet in one direction, a cover for the chamber retaining the rollers in place, and means to rotate the pinion. 100

The foregoing specification of my improvements in electro-mechanical lamps signed by me this 2nd day of March, 1922.

PAUL BLOT.
